UNITED STATES PATENT OFFICE.

EDWARD P. HATCH, OF LAGRANGE, ILLINOIS.

BARREL-HEAD.

SPECIFICATION forming part of Letters Patent No. 741,332, dated October 13, 1903.

Application filed December 18, 1902. Serial No. 135,715. (No model.)

To all whom it may concern:

Be it known that I, EDWARD P. HATCH, a citizen of the United States, residing at La-
5 grange, in the county of Cook and State of Illinois, have invented a new and useful Im-
provement in Barrel-Heads, of which the fol-
lowing is a specification.

The invention relates to improvements in
removable and replaceable barrel-heads; and
10 my primary object is to provide particularly
efficient means for securing a removable and
replaceable barrel-head in place, whereby a
perfectly water-tight joint is insured between
the inner sides of the barrel and the barrel-
15 head.

The invention is illustrated in the accom-
panying drawings, in which—

Figure 1 is a view in perspective showing
the barrel-head secured in place; Fig. 2, a
20 view in sectional elevation taken on line 2 of
Fig. 1 and viewed in the direction of the arrow;
Fig. 3, a plan view of one of the clamp-
ing members; Fig. 4, a vertical sectional view
25 on line 4 of Fig. 3 and viewed in the direction
of the arrow; Fig. 5, a plan view of one of the
keys or wedges, and Fig. 6 an end view of the
wedge.

In the preferred construction illustrated, A
represents a barrel or cask body, which may
30 be of ordinary construction, having a flaring
portion a, forming an annular shoulder or
abutment a'. In the flaring part a near the
shoulder a' is an annular groove a², having
the upper side beveled, as shown at a³.

35 The barrel-head B may be of the ordinary
construction, but preferably cut away at such
an angle along its circumferential edge to form
an annular beveled seating portion b, so as to
cause the upper surface of the head B when
40 placed in position to be in a plane slightly
above the plane of the lower surface of the
groove a².

B' B' are companion clamping members,
each having a curved side b⁴, beveled along
45 its edge to form the segmental wedge-shaped
tongue b' and converging sides b², said con-
verging sides being provided with tongues b³,
cut away near the point of convergence, as
shown in Fig. 3. The clamping members
50 may be further provided with slots or elon-

gated perforations b⁴, through which may ex-
tend retaining-screws b⁵, rigidly secured to the
barrel-head. Thus the clamping members are
held to the barrel-head to prevent the parts
becoming detached and lost, the slots serving 55
to allow the clamping members to be given the
range of movement required. Wedges or keys
C, provided on opposite sides with grooves c
and having converging sides corresponding
with the opposed converging sides of the 60
clamping members, are insertible into and
removable from the space between the clamp-
ing members, so that the grooves c register
with the tongues b³.

The use of the invention is simple. In at- 65
taching the cover to the barrel the wedges or
keys are drawn toward each other to permit
the clamping members to be also moved to-
ward each other to draw the outer curved
edges of the clamping members within the 70
outer edge of the barrel-head. The head car-
rying the clamping members is lowered into
the barrel until its bevel seating-surface b
rests on the shoulder or abutment a'. The
wedges or keys C are then with any suitable 75
device, such as a hammer, forced along the
sides of the clamping members in a direction
opposite to each other, thus giving a corre-
sponding movement to the clamping mem-
bers. This movement of separation of the 80
clamping member advances the segmental
wedges or tongues b' into the bevel-groove a²,
the bevel-surface of the clamping members
engaging the corresponding bevel-surface a³
of the annular groove, causing the clamping 85
members to exert a downward pressure on
the barrel-head. This downward pressure
causes the seating-face b of the head to im-
pinge against the annular abutment or shoul-
der a'. Thus the head may be forced against 90
the shoulder a' as firmly as desired to insure
a perfect joint. In fact, the corner presented
by the shoulder a' would indent itself slightly
in the seating-face b. The wedges thus sepa-
rated are held in position by the pressure of 95
the clamping members against their sides.

If desired, the slots b⁴ and retaining-screw
b⁵ may be dispensed with and various changes
in minor details of construction may be made
without departing from the spirit of the in- 100

vention as defined by the claim. Hence no undue limitation is to be understood from the foregoing detailed description.

What I claim as new, and desire to secure 5 by Letters Patent, is—

In a barrel, the combination of a body portion provided near one end with a recess presenting a sharp annular shoulder, a groove beyond said recess having an inclined outer 10 side, a barrel-head having an annular beveled circumferential face resting upon said shoulder, spreading clamping members upon said head having wedge-shaped edges to engage said groove, and wedging means for

spreading said clamping members, the peripheral edge of the barrel-head being thicker than the distance between said sharp shoulder and said groove, whereby as the clamping members are spread apart their wedge-shaped edges enter said groove and press the 20 barrel-head upon said sharp shoulder to be indented thereby, substantially as and for the purpose set forth.

EDWARD P. HATCH.
